BRUSH HANDLE

Murray Schotland, New York, N.Y., assignor to Gibson-Thomsen Co., Inc., a corporation of New York

Filed Apr. 2, 1969, Ser. No. 16,557

Term of patent 14 years

Int. Cl. D4—02

U.S. Cl. D4—35

FIG. 1 is a top plan view of a brush handle embodying my new design;

FIG. 2 is a side elevational view of the new design;

FIG. 3 is a bottom plan view of the new design;

FIG. 4 is an end elevational view of the new design; and FIG. 5 is another end elevational view from the opposite direction of the new design.

The broken lines are shown for illustrative purposes only and form no part of the drawing.

I claim:

The ornamental design for a brush handle, substantially as shown and described.
